(57) **CLAIM**

I claim the ornamental design for a dental patient face shield, as shown and described.

DESCRIPTION

FIG. 1 is a front perspective view of a dental patient face shield shown in an environmental of use on a patient, showing my new design.

FIG. 2 is a rear view thereof.

FIG. 3 is a left side view thereof.

FIG. 4 is a right side view thereof.

FIG. 5 is a top view thereof.

FIG. 6 is a bottom perspective view thereof; and,

FIG. 7 is a front perspective view from the left side thereof. The broken lines depicting a person shown in FIG. 1 are environmental matter forming no part of the claimed design.

1 Claim, 7 Drawing Sheets
